[57] **CLAIM**

The ornamental design for a wall plate for double electric socket, as shown and described.

DESCRIPTION

FIG. 1 is a front elevational view of a wall plate for double electric socket, showing our new design; FIG. 2 is an edge elevational view of the same taken looking downwardly from above FIG. 1; FIG. 3 is a side elevational view thereof. The side opposite that shown in FIG. 1 is unornamented.
